UNITED STATES PATENT OFFICE

ROBERT GRAHAM FLEMING, OF CHICO, CALIFORNIA, ASSIGNOR TO GUY H. HALL, OF EVANSTON, ILLINOIS

THRASHING MACHINE

Application filed January 23, 1930. Serial No. 422,792.

My invention relates to that class of thrashing machines in which there is employed a rotary cylindrical brush with flexible wire bristles and co-operating with baffle plates spaced apart from each other with pockets between them, such, for instance, as illustrated in my application for patent Serial No. 317,942, filed November 8, 1928, for harvesters.

10 The objects of my present invention are, first, to provide an improved structure of the baffle devices whereby the grain being thrashed is held in the path of action of the rotary wire brush for a short period of time 15 before entering the adjacent pocket, and, at the same time to permit threshed grain and chaff to pass into the pocket as soon as it is separated from the heads or stalks, and to remove from the grains all portions of the hulls 20 under such conditions as when the hulls are not thoroughly ripe or the straw is wet.

A further object is to provide improved means for forcing the stalks of grain into the space between the rotary brush and the 25 first baffle plate, said means being so arranged that when a dry corn stalk, stiff weed or other similar article is being carried by the conveyor toward the thrashing brush and engages the auxiliary feeding conveyor, the 30 auxiliary conveyor will yield and thereby prevent injury to the conveyors.

My invention consists in the construction, arrangement and combination of the various parts of the device, whereby the objects contemplated are attempted, as hereinafter more 35 fully set forth, pointed out in my claims, and illustrated in the accompanying drawings, in which:

Figure 1 shows a vertical, transverse sectional view of my improved machine.

Figure 2 shows an enlarged detail plan view of a part of my improved baffle device.

Figure 3 shows an enlarged detail sectional view of my improved baffle device on the line 45 3-3 of Figure 2.

Figure 4 shows a detail sectional view illustrating the yielding feature of the auxiliary feeding conveyor.

Referring to the accompanying drawings, 50 I have used the reference numeral 10 to indi-

cate generally the frame of the thrashing device. Mounted in this frame is a large roller 11, around which there is passed a slatted conveyor 12.

Adjacent to the roller 11 there is mounted 55 a rotatable shaft 13, to which is fixed a cylindrical brush having bristles 14 made of flexible spring wire. Surrounding the top, rear, and bottom portions of the brush is a casing 15, spaced apart from the brush far enough 60 to permit the accumulation therein of considerable quantities of grain and chaff, and to form with the baffles hereinafter referred to, a series of pockets 16.

The baffle devices each comprise a plate 17 65 fixed to the casing 15 and extended inwardly radially of the casing. It is then bent and inclined outwardly and toward the receiving end of the casing to form a guide plate 18, the outer end of which is fixed to the casing 15. 70

A flat metal plate 19 which extends the full length of the member 17 is adjustably secured to the member 17 by means of bolts 20 extended through slots 21 in the plate 17, so that the outer edge of the plate 19 may be adjusted to 75 the desired position for defining the space between the outer edges of the brush bristles and the baffle devices.

On the side of the plate 19 opposite from the plate 17, I have mounted a segmental 80 shaped screen plate 22, extending the full length of the baffle device, and shaped to substantially conform to the contour of the rotary brush. This plate is provided with a series of staggered openings 23, which openings are 85 large enough to permit grain and chaff to pass readily through it and also small heads or portions of heads of unthrashed grain, and this plate 24 performs the double function of a screen and a temporary retarding device. 90

The operation of the brush, baffle plate and pocket elements just described is as follows: When grain to be thrashed is delivered to the brush adjacent to the first inclined plate 18, this plate deflects the grain to the space between the baffle device and the brush and the heads are then temporarily retarded by the baffle device and held in the path of action of the spring wire bristles. I have found in my tests that when the brush runs at a speed 95 100

- of about 1,000 R. P. M. the action of the flexible wire bristles upon the grain when it is temporarily retarded by the baffle device is such that nearly all of the hulls are removed from the kernels, and, in addition thereto, substantially all of the heads are removed from the straws. After the heads pass the baffle member 19, they are then moved over the combined screen and retarding plate 22, and during this movement the heads and grains tend to move outwardly away from the brush both through the pressure of the spring bristles and centrifugal action, and obviously as the separated grains and chaff and portions of the heads that have been separated from the straws pass over these plates 22, some of them will pass through the openings 23 into the pocket 16. During this action upon the heads and grains, I have found by actual tests that the straws from which the heads are separated will be engaged by such a considerable portion of the circumference of the brush that they will be carried with the brush right through the device without entering the pockets. It is true that short pieces of straw enter the pockets, but in practice substantially every long straw passes through the entire device at the speed of the brush movement and without being retarded in the pockets. Such portions of the grains, chaff and heads as enter the pockets, either through the openings 23 or the space between the screening and retarding plate 22 and the next baffle plate, are temporarily retarded in their progress through the machine and in practice the pockets are normally almost full of these materials. These materials enter the pockets at the upper end and are gradually moved both by gravity and the frictional engagement of the brush bristles, toward the lower end, and then thin layers of these materials are thereby forced from the delivery end of the pocket by the inclined portion of the second baffle device and are again presented to the action of the brush bristles, and when these materials are again presented to the brush, the materials will be in a position relatively stationary as compared with the rapidly moving bristles of the brush, so that the impact of the rapidly moving bristles upon the stationary materials will have the effect of removing hulls from the grains. I have obtained very satisfactory results in my tests without the use of the combined screen and retarding plates and, hence, they are not essential to the successful operation of the machine. In Figure 1 I have illustrated a large object, such, for instance, as a stone, indicated by the reference numeral 24, and this article is shown as lodged between the second baffle device and the brush. The article is obviously much larger than the space between the bristles and the baffles. In actual practice such articles, however, pass readily through the device without damage to the machine because the flexible spring bristles of the brush spread apart far enough to receive such article and the article is then carried to a delivery point while imbedded between the bristles as illustrated in Figure 2, and after the article has thus passed through the brush, the bristles return to their normal position because of their resiliency. In practice it sometimes happens that large objects, such, for instance, as green weeds, will be fed into the machine, the thickness of which is greater than the space between the bristles and the baffle devices, and when this occurs, I have found that these large soft objects also imbed themselves between the bristles and are carried through the machine without being retarded by the baffles and without entering the pockets, and when they pass out of the machine, they are not ground to a fine pulp and mixed with the thrashed grain, due to the fact that the main body of such weed is imbedded between the bristles until the last baffle has been passed and then it is discharged by centrifugal action. In connection with large weeds or the like, I have found the plates 22 to be advantageous in preventing the entrance of green weeds and the like into the pockets and in retaining them imbedded in spaces between the bristles. For the purpose of forcing material to enter the space between the first baffle device and the brush, I have provided a slatted conveyor 25, passing over to rollers 26 in a substantially horizontal plane and moving in the direction of the arrows as shown in Figure 1. One of the rollers 26 is placed as near as possible to the first baffle device, and the two rollers are placed on opposite sides of the top portion of the large roller 11, and one of the rollers 26 is mounted upon movable bearings held away from the other roller 26 by springs 27. The conveyor itself is made of flexible material. The advantage of this structure is that, as illustrated in Figure 4, when a large and unyielding object, such, for instance, as a corn stalk and indicated by the reference numeral 28 in Figure 4, is carried upwardly and rearwardly by the conveyor 12, it will engage the lower surface of the conveyor 25 between the rollers 26 and conveyor 25 will yield and then the spring mounted roller will also yield so that the article may go through without injuring the conveyors. After all the material has passed beyond the last baffle device, this material is thrown with considerable force in the direction indicated by the arrow shown in Figure 1, and I have constructed the device so that the large roller 11 is directly in the path of the material being discharged from the last baf-

ble device, and, since this roller and its conveyor are moving downwardly and forwardly at this point, all of the material is directed to pass under the roller 11.

5 For the purpose of separating substantially all of the long straws from the combined grain and chaff, I have provided a transverse bar 29 pivotally mounted on the side of the frame below the lower plate 22 and fixed to this bar are a series of rods 30, only one of which is shown in Figure 1, and these rods are extended forwardly and downwardly with their forward ends only engaging the conveyor 12. By this arrangement, it is obvious that when the cross slabs on the conveyor 12 engage the ends of these rods, they will force them downwardly, and they will again be moved upwardly by the action of the spring 31, so that said rods will be constantly vibrated by their engagement with the cross slats, and, preferably fixed to this bar 29, is a grain pan 32 to direct the chaff and grain into the conveyor 33, and by this arrangement it is obvious that pan 32 will be vibrated to advance the material into the conveyor 12.

I claim as my invention:

1. In a thrashing machine, the combination of a rotary cylindrical brush having flexible bristles, two baffle devices for directing material toward and temporarily holding it in the path of the brush, a pocket formed between the baffle devices, in which the smaller particles of the material being operated on are temporarily retarded and again presented to the action of the brush by the second baffle device, and a perforated retarding device, positioned adjacent to the first baffle device and extending a short distance toward the second baffle device and located close to the brush, for the purposes stated.

2. In a machine of the class described, the combination of a large roller, a slatted conveyor passing over the roller, a thrashing device for receiving material from the conveyor, means for directing the flow of material passing through the thrashing device toward the central portion of the said large roller, whereby said material will be carried by the slatted conveyor in the direction opposite to that from which it was delivered to the thrashing device, a series of rods pivotally supported below the large roller and presented to the slatted conveyor so that their ends only are engaged by the slatted conveyor, and yielding means for holding said rods toward the slatted conveyor whereby the action of the slatted conveyor engaging the rods will cause them to vibrate.

60 3. In a thrashing machine, the combination of a rotary cylindrical brush having flexible bristles, two baffle devices for directing material toward and temporarily holding it in the path of the brush, a pocket formed between the baffle devices in which the smaller

particles of the material being operated on are temporarily retarded and again presented to the action of the brush by the second baffle device, one of said baffle devices being adjustable toward and from the brush, for the purposes stated.

4. In a thrashing machine, the combination of a rotary cylindrical brush having flexible bristles, two baffle devices for directing material toward and temporarily holding it in the path of the brush, a pocket formed between the baffle devices in which the smaller particles of the material being operated on are temporarily retarded and again presented to the action of the brush by the second baffle device, one of said baffle devices comprising an inclined plate for directing material toward the brush, and an adjustable plate for defining the space between the baffle device and the brush.

ROBERT GRAHAM FLEMING.
